UNITED STATES PATENT OFFICE

2,468,201

HIGH LIFT SIDE-DELIVERY LOADER

Daniel S. Hoover, Mansfield, Ohio

Application June 27, 1946, Serial No. 679,739

3 Claims. (Cl. 214—132)

1

This invention relates to a high lift side-delivery loader, and has for one of its objects the production of a simple and efficient loader for scooping, lifting and dumping a load at a desired location.

A further object of this invention is the production of a simple and efficient means for bodily shifting the loading scoop and its support vertically of the supporting frame therefor.

Other objects and advantages of this invention will appear throughout the following specification and claims.

In the drawing:

Figure 1 is a side elevational view of the loader;

Figure 2 is a front elevational view certain parts being broken away and certain parts being shown in section;

Figure 3 is a detail perspective view of the scoop arms supporting shaft;

Figure 4 is a top plan view of the loader;

Figure 5 is a bottom plan view of the loader, certain parts being broken away;

Figure 6 is a sectional view taken on line 6—6 of Figure 5.

By referring to the drawing, it will be seen that 10 designates a support which is carried by a tractor 11 shown in dotted lines. A pair of forwardly extending arms 12 are carried by the yoke and secured at their rear ends, as at 13. Vertical braces 14 and 14^a are secured at their lower ends 13 and 13^a, and engage a pivoted inverted U-shaped member 15 at their upper ends 16. A rotary turn-table 17 is carried between the forward ends of the arms 12 and a vertical guide frame 18 is carried near the forward edge of the turn-table 17. This frame 18 comprises a pair of parallel angle members 19 having side flanges 20. These side flanges 20 are provided with aligned vertical side slots 21. The upper end of the frame 18 is braced by the rearwardly extending braces 22 which are anchored at their rear ends to the upper end of the U-shaped member 15.

A scoop or excavation tool 23 is supported by a yoke 24 pivoted at 25 and this yoke 24 is rigidly secured to the lower ends of the suspending arms 26. These arms 26 are journaled on the transverse shaft 27 for outward swinging movement. The shaft 27 carries elongated shoes 28 at its ends which slide in the aligned vertical slots 21 of the vertical frame 18. A forwardly extending bracket 29 is carried centrally of the shaft 27 and a hydraulic cylinder 30 is suspended therefrom. The plunger rod 31 of the cylinder 30 is secured to the brace rib 32 of the scoop 23, as shown in Figures 1 and 2.

2

A hydraulic cylinder or jack 33 is secured at one end to the turn-table 17 near the rear edge thereof, and at the opposite end to the transverse brace 34 which ties the arms 26 together below the journal thereof. As the cylinder or jack 33 is extended, the shoes 28 slide upwardly in the slots 21 to raise the scoop 23 to the dotted line position indicated as A in Figure 1. As the cylinder or jack 30 is extended, the shoes 28 will 5 abut against the upper ends of the slots 21 and the arms 26 will be swung further upwardly to raise the scoop 23 to the position indicated at B in Figure 1. The hydraulic cylinder 30 is actuated at that time under the control of the operator from the control station 35 to extend the plunger rod 31 and swing the bucket to a dumping position.

It should be understood that the hydraulic cylinders 30 and 33 are of the conventional type and 20 may be selectively controlled from the control station 35, which control station may be located at any suitable location on the tractor. Furthermore, any suitable lifting means may be substituted for the hydraulic cylinders if desired, without departing from the spirit of the invention.

The frame 10 carries a depending bracket 36 which supports a hydraulic jack or cylinder 37. The plunger 38 of the jack or cylinder 37 is secured to the links 12 and the jack or cylinder 37 is controlled from the control station 35 for raising and lowering the links 12 which carry the turn-table 17 and the frame 18 to the desired position.

A hydraulic motor 39 is hung from the turn-table 17 and carries a gear 40 which meshes with a gear 41. This gear 40 is keyed to the shaft 42 of the turn-table 17 and is adapted to rotate the turn-table in a selected direction as the motor 39 is operated. The motor 39 is operated from the control station 35. Any suitable motor or operating means may be substituted for the motor 39 if desired.

By rotating the motor 39 the scoop or tool 23 may be faced in the desired direction, since the 45 scoop 23 which is hung on the vertical frame 18 is carried by the turn-table 17. The scoop may be lowered to the desired depth by swinging the links 12 downwardly by operating the jack 37. The scoop is lifted and dumped to the positions A and B as above described.

It should be understood that certain detail changes in the mechanical structure may be employed without departing from the spirit of the invention, so long as such changes fall within the 55 scope of the appended claims.

Having described the invention, what is claimed is:

1. A loader of the class described comprising a support, a vertical frame, a turn-table rotatably mounted upon said support for turning the vertical frame in a selected direction, a tool-carrying means, said tool-carrying means comprising a hanger slidably pivoted at the upper end of said vertical frame, elevating means for elevating the hanger to a selected elevated position and then swinging the hanger outwardly to a selected position, said vertical frame having vertical guiding trackways at its upper end, a transverse shaft carried by said hanger, shoes carried at the ends of said shaft and traveling in said trackways, abutments at one end of said trackways against which said shoes abut for limiting the upward movement of said hanger, and said elevating means constituting means for swinging the hanger outwardly when said shoes abut the ends of said trackways.

2. A loader of the class described comprising a support, a vertical frame, a turn-table rotatably mounted upon said support for turning the vertical frame in a selected direction, a tool-carrying means, said tool-carrying means comprising a hanger slidably pivoted at the upper end of said vertical frame, elevating means for elevating the hanger to a selected elevated position and then swinging the hanger outwardly to a selected position, and means for raising and lowering said

turn-table and vertical frame which is carried by the turn-table to regulate the digging depth of said tool.

3. A loader of the class described comprising a support, a vertical frame, a turn-table rotatably mounted upon said support for turning the vertical frame in a selected direction, a tool-carrying means, said tool-carrying means comprising a hanger slidably pivoted at the upper end of said vertical frame, elevating means for elevating the hanger to a selected elevated position and then swinging the hanger outwardly to a selected position, trackways for said hanger, abutment means limiting the upward movement of said hanger, and said elevating means constituting means for swinging the hanger outwardly when said hanger abuts said abutment means.
